UNITED STATES PATENT OFFICE.

FREDERICK P. WOOD, OF DETROIT, MICHIGAN, ASSIGNOR TO AMERICAN CAN COMPANY, OF NEW YORK, N. Y., A CORPORATION OF NEW JERSEY.

COFFEE-CONTAINER.

1,203,832.

Specification of Letters Patent. Patented Nov. 7, 1916.

Application filed February 18, 1914. Serial No. 818,488.

To all whom it may concern:

Be it known that I, FREDERICK P. Wood, a subject of the Kingdom of Great Britain, residing in Detroit, in the county of Wayne 5 and State of Michigan, have invented a new and useful Improvement in Coffee-Containers, of which the following is a specification.

This invention relates to an improvement 0 in paper receptacles for aromatic food products, and the invention consists in combining with the paper walls of the receptacle a lining of parchmentized paper cemented to the inner surface of the paper receptacle by 5 a fused cement.

In the accompanying drawing which forms a part of this specification, Figure 1 0 is a perspective view of an ordinary coffee carton containing this invention. Fig. 2 is 0 a horizontal fragmentary section of the same taken on the line 2—2 of Fig. 1.

It has long been known that parchmentized paper is to some considerable degree impervious to the aromatic oils of roasted and 5 ground coffee and that it is a useful material with which to line paper packages intended to hold teas. And it is also known that an intercalated layer of fused cement, such for example as asphaltum, etc., will prevent the 0 access of moisture to the interior of a paper container. I have found by a series of experiments that if a receptacle or carton be made of paper and covered on the inside

with a fused cement, to which is made to adhere while still hot a lining of parchmentized paper or hydrolyzed fiber that the wholly unexpected result is produced of a package not merely inaccessible to moisture but wholly impervious to aromatic oils to such extent that the package will not long continue to smell of its aromatic contents after they are poured out, which shows that none of the aromatic oils are absorbed.

In the accompanying drawing A represents an ordinary coffee carton, B is a lining 45 sheet of hydrolyzed fiber or parchmentized paper and C is the intercalated layer or coating of fused cement which causes the paper B to adhere at all points to the carton wall A.

I claim:

A paper walled container the walls of which consist of an exterior layer of paper; an interior layer of hydrolyzed fiber; and an intermediate layer of fused cement adhering to and uniting said exterior and interior layers; said fused cement and hydrolyzed fiber coöperating to prevent the absorption 55 of aromatic oils and thereby to preserve the flavor and prevent the deterioration of the 60 contents of said container.

FREDERICK P. WOOD.
